UNITED STATES PATENT OFFICE.

JOSÉ SAMPERE, OF NEW YORK, N. Y.; MARIE SAMPERE, ADMINISTRATRIX OF SAID JOSÉ SAMPERE, DECEASED, ASSIGNOR, BY MESNE ASSIGNMENTS, TO AEOLIAN COMPANY, OF NEW YORK, N. Y., A CORPORATION OF CONNECTICUT.

ATTACHMENT FOR COUPLING AUTOMATIC PIANOS OR ORGANS AND PHONOGRAHS TOGETHER.

1,057,458.

Specification of Letters Patent.

Patented Apr. 1, 1913.

Application filed December 30, 1908. Serial No. 470,090.

To all whom it may concern:

Be it known that I, JOSÉ SAMPERE, a subject of the King of Spain, and resident of the borough of Manhattan, city, county, and State of New York, have invented certain new and useful Improvements in Attachments for Coupling Automatic Pianos or Organs and Phonographs Together, of which the following is a specification.

My invention relates to attachments for coupling together automatic pianos organs, or other pneumatically operated musical instruments, and phonographs so as to secure a simultaneous and harmonious operation thereof for the purposes, for instance of producing a vocal selection on the phonograph with an accompaniment on the piano or organ, etc., and has for its object to provide a simple and effective attachment of this character, which will automatically regulate the operation of the two instruments so as to secure a perfect co-operation between the two.

Other objects will appear from the specification hereinafter and the features of novelty will be pointed out in the appended claims.

Reference is to be had to the accompanying drawings in which—

Figures 1 and 1^a represent a diagrammatic view partly in elevation and partly in plan showing my new attachment connected with a piano and a talking machine. Fig. 2 is a sectional plan view of a portion thereof on the line 2—2 of Fig. 1 and Fig. 3 is an elevation of the sound record support with the sound record shown thereon in section.

A represents the usual stationary frame for supporting the tracker board B and in which the customary music rolls C, C' carrying the music sheet D are journaled.

E is the drive shaft on which is mounted to rotate therewith a pinion G arranged by the shaft C³ on which the roller C is mounted. A sprocket wheel E' is loosely carried by the shaft E and is connected through the medium of a sprocket chain E² with a sprocket pinion E³ which is secured to a shaft C² on which the roller C' is mounted.

E⁴ is a clutch of the usual kind secured to the shaft E and arranged to be engaged

with the sprocket E' during the re-rolling operation. The drive shaft E also carries a sprocket wheel F which is connected by means of a sprocket chain F' with another sprocket wheel F² mounted on the motor shaft F³. The motor F⁴ may be of any usual construction adapted for the purpose and is connected with the shaft F³ in the well known manner. Thus as the motor is operated the roller C will be rotated in a direction to wind the music sheet thereon, the roller C' meantime running free. Of course it is to be understood that during the playing of the selection the clutch E⁴ and the sprocket E' are disengaged so that the sprocket E' runs free. After the selection has been finished the clutch E⁴ is thrown into engagement with the sprocket E' and the pinion G is thrown out of engagement with the gear G'. In this position of the parts the motor will drive the shaft E and with it the sprocket E' which in turn, through the medium of the chain E² will rotate the sprocket pinion E³. This will cause the roller C' to be rotated in the opposite direction and will re-roll the music sheet. So far the mechanism described may be of the usual kind in self-playing pianos or organs and forms no part of my invention.

In automatic pianos in which my attachment is used, the two end openings B' and B² of the tracker board B instead of being connected directly with the extreme sound producing devices respectively are connected by means of tubes H, H' with valve blocks H² and H³ respectively. The valve block H² is connected through the medium of a tube H⁴ with the extreme sound producing device at the left hand end of the key board and the block H³ is connected by means of a tube H⁵ with the extreme sound producing device at the right hand end of the key board. The block H² is further connected with a diaphragm chamber I by a tube H⁶ and the block H³ is connected with a diaphragm chamber J through the medium of a tube H⁷. Valves K and K' are slidably mounted respectively in the blocks H² and H³ and are connected to move in unison by a rod K². The valve K is provided with a passage K³ so arranged as to bring either the tubes H and H⁶ into

communication with each other, or to connect the tubes H and H^4 according to the position of the valve. The valve K' is provided with a similar passage K^3 adapted to either connect the tubes H' and H^7 or to bring the tubes H' and H^5 into communication with each other as desired. The valves K and K' are so connected with each other that when the tubes H and H^6 are in registry the tubes H' and H^7 will be in communication with each other and when the tubes H and H^4 are connected, the tubes H' and H^5 will communicate with each other. A rod K^4 serves to connect the valve K' with a lever L pivoted at L' to a stationary part of the instrument and provided with an operating rod L^2 . Thus as this operating rod L^2 is moved to the right or left, the valves K and K' will be shifted. The lever L is also connected by means of a rod L^3 with a valve M located in a valve chamber M' and controlling an opening M^2 . This opening M^2 communicates with a chamber M^3 which is connected with the motor governor by a pipe or tube M^4 . The chamber M' is connected with the motor F^4 through the medium of a tube M^5 . A second opening M^6 controlled by a valve N also connects the chambers M' and M^3 the purpose of which will be more fully described hereinafter. The valve N carries a rod N' which is secured to the movable member of a master pneumatic N^2 mounted upon a support N^3 . The pneumatic N^2 is connected by means of a passageway N^4 with a chamber N^5 having an opening N^6 extending to the atmosphere and another opening N^7 extending to a chamber J' . Puppet valves O and O' control the openings N^6 and N^7 and are mounted on a stem O^2 secured to a head O^3 carried by a diaphragm O^4 which closes a diaphragm chamber J^2 . A second diaphragm O^5 closes the diaphragm chamber J and carries a head O^6 to which a stem O^7 is secured on which puppet valves O^8 and O^9 are mounted. These valves O^8 and O^9 are located in a chamber P connected by means of a channel P' with a minor pneumatic P^2 also mounted on the support N^3 and control respectively an opening P^3 which communicates with the atmosphere and an opening P^4 which connects the chamber P with the chamber J' . The pneumatic P^2 is connected with the pneumatic N^2 by means of a rod P^5 in such a manner that when the one pneumatic is expanded the other will be collapsed. The pneumatics N^2 and P^2 are provided respectively with regulating screws N^8 and P^6 mounted on the movable member of each pneumatic and having their inner ends each provided with a cushion N^9 and P^7 . These cushioned ends are arranged to abut against the fixed member of each pneumatic to limit the collapsing movement of the movable member. The

chamber J' is connected by means of a tube I' with another chamber I^2 above a diaphragm I^3 which closes the diaphragm chamber I . This diaphragm I^3 carries a head I^4 to which is secured a stem I^5 on which are located the puppet valves I^6 and I^7 located in a chamber I^8 . The puppet valve I^6 controls an opening I^9 , extending from the chamber I^8 to the atmosphere and the valve I^7 controls an opening I^{10} connecting the chamber I^8 with the chamber I^2 . All of the stems I^5 , O^2 and O^7 are guided respectively in cross pieces I^9 , O^{10} and O^{11} in the customary manner. A tube I^{10} extends from the chamber I^2 to the main reservoir (not shown), the connection being such as to insure a steady exhaust in the chamber I^2 and J' . The chamber I^8 is connected through the medium of a tube Q with a channel R located in a block R' which channel R extends to a pneumatic R^2 supported on the said block R' . The block R is preferably arranged within the usual casing of a phonograph S having a rotatable sound record support S' operated by the usual driving mechanism (not shown).

The movable member of the pneumatic R^2 carries an extension R^3 adapted to operate the bell crank member T of the customary starting and stopping mechanism. The said bell crank T is pivoted at T' and the one member thereof is arranged to project beneath the sound record support S' and engage the pin S^3 to hold the said sound record support against rotation. A spring S^4 tends to maintain said bell crank T in its formal position and to return it to said normal position to stop the phonograph. The movable member of the pneumatic R^2 further carries a cam member U extending adjacent to the periphery of the sound record support for the purpose to be more fully described hereinafter.

V is a catch pivoted at V' on the block R' and adapted to engage the said movable member of the pneumatic R^2 to hold it in its collapsed condition. The said catch is pressed toward the pneumatic R^2 by a leaf spring V^2 and is further provided with a finger piece V^3 for disengaging it from the pneumatic R^2 .

A lever W is pivoted at W' to a block W^2 suitably secured to the casing of the phonograph and carrying at its one end a roller W^3 and at its other end a valve W^4 . This lever is supported so that the roller W^3 engages the periphery of the sound record support S' , which is provided with a projection S^5 extending partly around said periphery to periodically swing the said lever W on its pivot. The valve end of the lever W is located opposite the end of a channel W^6 which extends through the block W^2 , and is connected by means of a tube W^7 with the diaphragm chamber J^2 . A spring W^8 main-

tains the roller W^3 in engagement with the periphery of the support S' . The record disks which are used in conjunction with my improved attachment are preferably provided with a recess X extending toward the periphery of the record X' from the beginning of the sound groove in said record, in the direction in which the record rotates. This recess is arranged to receive the stylus 5 and guide it to the sound groove, as the record is rotated. The records are further preferably provided with an opening X^2 arranged to one side of the usual central aperture and adapted to take over a pin S^6 secured to the support S' for positioning the record thereon. The music sheet D at a point along its one edge corresponding with the opening B^2 of the tracker board B , is provided with a series of spaced apertures 10 D' and at the other edge opposite the beginning of the selection has a single opening D^2 adapted to register with the opening B' of the tracker board B .

In operation, if it is desired to play the 25 two instruments simultaneously and harmoniously, the operating rod L^2 is moved toward the right in Fig. 1 thus swinging the lever L on its pivot L' . This will cause the valves K and K' to assume the position 30 shown in Fig. 1 and establish communication between the tubes H and H^6 and between the tubes H' and H^7 . At the same time the valve M is moved over the opening M^2 to completely close it so that the air from 35 the motor is exhausted through the tube M^4 , chamber M^3 , opening M^6 , chamber M' and tube M^5 . The passage from the motor governor to the motor is thus controlled by the valve N . As the motor now drives the roll 40 C , the music sheet will be gradually wound thereon and the moment the opening D^2 comes over the opening B' of the tracker, air will rush into the tube H and H^6 and into the diaphragm chamber I , causing the diaphragm to be lifted and the valves I^6 and I^7 45 to be raised. This will close the opening I^x and shut off communication between the chamber I^8 and the atmosphere and will open the opening I^9 and establish communication between the chamber I^2 and I^8 . The air in the chamber I^2 having meanwhile 50 been exhausted through the pumping of the usual pedals and bellows the air will be drawn from the chamber I^8 , the tube Q and channel R and the pneumatic R^2 will be collapsed. As this takes place the projection R^3 will swing the bell crank T away from the pin S^3 leaving the sound record support 55 free to be rotated by the usual driving mechanism. Further as the said pneumatic collapses the cam member U will engage the periphery of said sound record support and will exert a sudden push thereon, and immediately start the support rotating at the 60 maximum speed at which the mechanism is set. This does away with the customary gradual starting of the phonograph. It is of course to be understood that the sound record has been placed in position on the support before this with the stylus in the recess X . Both selections are thus automatically started simultaneously. Through the medium of the tube I' the air in the chamber J' is also exhausted as long as the 65 pedals are operated. Meanwhile as the 70 openings D' pass successively over the opening B^2 of the tracker air rushes through the tubes H' and H^7 and causes the diaphragm to move up and down alternately raising and lowering the valves O^8 and O^9 and opening and closing the openings P^3 and P^4 . At the same time as the sound record support is rotated, the projection S^5 each time it comes around and passes, will swing the lever W on its pivot and will open and close 75 the channel W^5 . Air will thus rush in in short gusts through the channel W^5 and the tube W^6 to the diaphragm chamber J^2 and will cause the diaphragm O^4 to move up and down and raise and lower the valves O 80 and O' and alternately open and close the openings N^6 and N^7 . The pneumatics N^2 and P^2 will thus be alternately subjected to the influence of atmospheric pressure and of the exhaust in the chamber J' through the 85 channels N^4 and P' . As long as the speed of the two instruments is the same this will have no appreciable effect on the valve N . If, however, the speed of the phonograph is 90 greater than that of the piano, the projection S^5 will come around with greater rapidity and the lever W and valve W^4 will be operated oftener in a given time. The channel W^5 will therefore be open practically continuously and the valve O' will be 95 held in its raised position so that the air in the pneumatic N^2 will be more nearly exhausted and the said pneumatic will overcome the resistance of the pneumatic P^2 and will collapse, thus moving the valve N further to the left in Fig. 1 and uncovering the 100 opening M^6 to a greater extent. This will cause the motor F^4 to travel faster until the speed of the piano agrees with that of the phonograph. In the same way if the speed 105 of the piano exceeds that of the phonograph, the openings D' will travel over the opening B^2 with greater rapidity and the valve O^9 will be maintained in its raised position a greater length of time. The air in the pneumatic P^2 will thus be more nearly exhausted and the pneumatic will collapse and overcome the resistance of the pneumatic N^2 110 which is at this time not exhausted. The valve N will by this operation be moved further to the right in Fig. 1 and will more nearly cover the opening M^6 and will cause the motor to slow down until the two speeds 115 agree. As soon as the projection S^5 again operates the valve W^4 the 120 125 maximum speed at which the mechanism is

pneumatic N^2 will be collapsed and owing to its larger size will return the valve N to the position it occupied just before the pneumatic P^2 had been collapsed. This prevents the piano from continuing to run at its temporarily decreased speed and thus continue to run behind the phonograph throughout the selection. Each time after the pneumatic P^2 has been operated to move the valve N to the right in Fig. 1, the pneumatic N^2 will return said valve to its initial position the moment the projection S^5 operates the valve W^4 . It is to be understood that the speed of the phonograph is substantially uniform throughout the selection and that the speed of the piano is regulated accordingly. In other words the speed of the phonograph is the governing speed and the piano speed is made to accommodate itself thereto. It is to be further understood that the projection S^5 extends about one-sixth of the distance around the periphery of the sound record support and that the dimensions of each opening D' is such that it will remain over the opening B^2 as long as the said projection operates the valve W^4 . The distance between the openings D' corresponds to the remaining five-sixths of the periphery of the sound record support. The openings D' are so located relatively to the opening D^2 that when the instruments are started the first opening D' will travel over the opening B^2 an instant before the projection S^5 opens the valve W^4 ; each succeeding opening D' will accordingly travel over the said opening B^2 a trifle in advance of the time the valve W^4 is operated. The two pneumatics N^2 and P^2 are thus operated one after the other so that in the operation of the mechanism the valve N will be spasmodically moved back and forth to a slight degree as the instruments run in harmony. The pneumatic N^2 is larger and of greater power than the pneumatic P^2 and is operated an instant later as before stated and not simultaneously therewith so that the tendency of the pneumatic N^2 to force the valve N to the right in Fig. 1 and thus retard the motor is overcome. If the openings D' and the projection S^5 worked simultaneously there would be danger of one of the openings D' continuing over the opening B^2 after the projection S^5 had ceased to maintain the valve W^4 in its open position, which would cause the pneumatic P^2 to be collapsed and overcome the pneumatic N^2 and the valve N to be moved to the right thus diminishing the speed of the piano at the wrong time. In the present construction after the piano has been slowed down, the valve W^4 will be operated as described above which will cause the master pneumatic N^2 to collapse and move the valve N to the left in Fig. 1. The opening M^6 will thus be exposed to a greater extent and the mo-

tor F^4 will increase in speed and the speed of the music sheet D until the speeds of the two instruments again agree.

The regulating screws N^6 and P^6 are provided for the purpose of regulating the collapse of the pneumatics N^2 and P^2 so as to secure a proper coöperation of the said pneumatics and the valve N . The speed of the two instruments is thus automatically regulated and governed so that it is impossible for one to run ahead of the other for any noticeable length of time and absolute harmony in the operation of the two instruments is secured.

When it is desired to use the automatic piano without the phonograph, the rod L^2 is moved to the left. This will cause the valves K and K' and M to be moved to the right and will establish communication between the tubes H and H^4 and the tubes H' and H^7 . The openings B' and B^2 will in this position of the parts communicate respectively with the extreme sound producing devices. With my device it is therefore possible to easily and simply couple the two instruments together and to automatically secure perfect coöperation between the two without the necessity for the adjustment of intricate mechanism.

Instead of having the openings B' and B^2 connected respectively with the valve blocks H^2 and H^7 , these openings may be connected directly with the first and last note of the action as is customary and additional openings may be provided in the tracker board adjacent to the openings B' and B^2 with which the blocks H' and H^2 might be connected. In this case the valves K^2 would be constructed to connect and disconnect the tubes H and H^6 and H' and H^7 respectively. The structure described hereinbefore may be easily installed in existing constructions of pianos and phonographs without material change and difficulty.

I have connected the two opposite extreme openings B' and B^2 of the tracker board with valve blocks H^2 and H^7 respectively as this is an easy and simple method of applying my improvement to existing structures without necessitating radical changes.

Various modifications may be made without departing from the spirit of my invention as defined in the claims.

I claim as my invention:

1. The combination of two musical instruments, pneumatic mechanism for driving one instrument, independent mechanical means for driving the other instrument, and means connecting the two instruments including mechanism controlled by said mechanical driving means for regulating the speed of the pneumatic mechanism.

2. The combination of two musical instruments, pneumatic mechanism for driv-

ing one instrument, independent mechanical means for driving the other instrument and means connecting the two instruments including pneumatically operated mechanism controlled by said mechanical driving means 5 for regulating the speed of the pneumatic mechanism.

3. The combination of an automatic piano and a phonograph provided with a rotatable sound record support, means connecting the two instruments including mechanism for regulating the speed of one instrument relatively to that of the other and means actuated by said sound record support for controlling said mechanism.

10 4. The combination of an automatic piano and a phonograph, a connection between the two, mechanism for simultaneously starting the two instruments together and pneumatic 20 means for immediately starting the phonograph at the maximum speed at which it is set.

25 5. The combination of an automatic piano and a phonograph, a motor for operating said piano, a speed regulating mechanism connected with said motor, a connection from said speed regulating mechanism to said phonograph and a valve automatically operated by said phonograph to control said 30 speed regulating mechanism to regulate the speed of the piano.

35 6. The combination of an automatic piano and a phonograph, a motor for operating said piano, mechanism for driving said motor, a valve chest with which said motor and said driving mechanism are connected, a valve in said valve chest governing the connection between the driving mechanism and the valve chest, pneumatic means controlling said valve and mechanism connected with and operated by said phonograph for controlling said pneumatic means to shift said valve in one direction or the other to regulate the speed of said motor.

40 45 7. The combination of an automatic piano, and a phonograph having a rotatable sound record support, a connection between the two, pneumatic means in said connection for controlling the speed of the piano, and a 50 valve operated by said sound record support and controlling said pneumatic means.

55 8. The combination of an automatic piano and a phonograph having a rotatable sound record support, a connection between the two, pneumatic means in said connection for controlling the speed of the piano, a valve for controlling said pneumatic means and a projection on said sound record support for operating said valve.

60 65 9. The combination of an automatic piano and a phonograph having a rotatable sound record support, a connection between the two, mechanism for simultaneously starting both instruments and a device arranged to engage the periphery of said sound record

support to immediately start the phonograph at the maximum speed at which it is set.

10. The combination of an automatic piano having a tracker board and an action, and a phonograph, a valve block, a connection from said valve block to the tracker board, a second connection from said block to the action, a third connection from said valve block to the phonograph and a valve movable in said block to bring either the first and second connections into communication with each other or to bring said first and third connections into communication with each other.

70 11. The combination of an automatic piano and a phonograph operatively connected therewith and having a rotatable sound record support, pneumatic means for controlling the speed of the piano and means operated by said sound record support for controlling said pneumatic means.

75 12. The combination of an automatic piano and a phonograph operatively connected therewith, pneumatic means for controlling the speed of the piano, a valve for controlling said pneumatic means and means connected with said phonograph for operating said valve.

80 13. The combination of two musical instruments, pneumatic mechanism for driving one instrument, independent mechanical means for driving the other instrument, a connection between the two instruments, means in said connection operated by said 95 mechanical driving means for regulating the speed of the pneumatic mechanism, and a device for disconnecting the two instruments without affecting the separate operation of either or necessitating the disengagement of said instruments.

90 14. The combination of an automatic piano and a phonograph connected together to work in unison, a tracker board in said piano, a valve block, a connection from said 100 tracker board to said valve block, a valve chest having a tension chamber, a connection from said valve chest to said valve block, a valve in said valve block controlling the connections between the tracker board and said block and between the valve chest and said block, a device for giving an impetus to the phonograph, a connection from said valve chest to said device, a valve in 105 said valve chest arranged to connect or disconnect said compression chamber with or from said device to operate same and a music sheet provided with an aperture arranged for coöperation with the tracker board to control the operation of said valve 110 in the valve chest.

115 15. The combination of an automatic piano and a phonograph connected together to work in unison, a tracker board in said piano, a valve chest having a pneumatic 120

125

power containing chamber; a connection from said valve chest to the tracker board, a device for giving an impetus to the phonograph, a connection from said valve chest to said device, a valve in said valve chest arranged to connect or disconnect said power containing chamber with or from said device to operate same, and a music sheet provided with an aperture arranged for co-operation with the tracker board to control the valve in the valve chest.

16. The combination of an automatic musical instrument and a phonograph having

driving mechanism connected therewith, pneumatic means for controlling the speed of the musical instrument, and means operated by said driving mechanism for controlling said pneumatic means.

In testimony whereof I have hereunto set my hand in the presence of two subscribing witnesses.

JOSE SAMPERE.
